US0D1078979S

(12) **United States Design Patent** (10) **Patent No.:** **US D1,078,979 S**
(45) **Date of Patent:** **** Jun. 10, 2025**

(54) **PORTABLE FAN**

(71) Applicant: **SHENZHEN JISU TECHNOLOGY CO., LTD.**, Shenzhen (CN)

(72) Inventors: **Jiefeng Tang**, Shenzhen (CN);
Wenpeng Qi, Shenzhen (CN)

(73) Assignee: **SHENZHEN JISU TECHNOLOGY CO., LTD.**, Shenzhen (CN)

(**) Term: **15 Years**

(21) Appl. No.: **29/935,733**

(22) Filed: **Apr. 3, 2024**

Related U.S. Application Data

(63) Continuation-in-part of application No. 29/917,050, filed on Nov. 16, 2023, now Pat. No. Des. 1,069,084.

(74) *Attorney, Agent, or Firm* — Daniel M. Cohn

(57) **CLAIM**

The ornamental design for a portable fan as shown and described.

DESCRIPTION

FIG. 1 is a perspective view of a portable fan showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the portable fan that form no part of the claimed design.

1 Claim, 8 Drawing Sheets
